UNITED STATES PATENT OFFICE.

ARVID J. MALMBERG, OF CLEVELAND, OHIO, ASSIGNOR TO THE R. F. CARPENTER MANUFACTURING COMPANY, OF CLEVELAND, OHIO, A CORPORATION OF OHIO.

HINGE CONSTRUCTION.

Application filed April 14, 1919. Serial No. 289,931.

To all whom it may concern:

Be it known that I, ARVID J. MALMBERG, a citizen of the United States, residing at Cleveland, in the county of Cuyahoga and State of Ohio, have invented certain new and useful Improvements in Hinge Constructions, of which the following is a specification.

This invention relates to hinges and particularly to that type of such devices known as gravity hinges.

In a patent of Carpenter and Anderson, No. 1,446,449, granted February 27, 1923, a hinge is shown of the gravity type provided with a partition clamp of an adjustable form so that the hinge may be adjusted to various thicknesses of partition. The present application relates to an improvement in the clamping means and to an arrangement of the upper and lower hinges whereby the upper hinge and the cam on the lower hinge form a stop for the door when in open position and prevent it from swinging too far and injuring the hinge parts.

Further details of invention will herein-after more fully appear from the following description, drawings, and claims.

Referring to the drawings, Fig. 1 is a view partly in elevation and partly in section showing the hinges applied to a door and frame; Fig. 2 is a similar view of the door thrown to one side or in open position; Fig. 3 is a section upon the line 3—3 looking in the direction of the arrows indicated in Fig. 1; Fig. 4 is a section on the line 4—4 of Fig. 2 looking in the direction of the arrows indicated therein; Fig. 5 is a perspective view of the upper hinge member alone; Fig. 6 is a perspective view showing the adjustable clamping means applied to the door engaging member; Fig. 7 is a view showing a modified form of lower hinge structure with the door in closed position; Fig. 8 is a view partly in elevation and partly in section, with the door swung into open position; and Fig. 9 is a section upon the line 9—9, of Fig. 8.

In the drawings, 1 represents a suitable frame or partition, and 2 represents a door which is to be hinged to the frame or partition by hinges which form the subject matter of this invention.

The upper hinge structure comprises a frame hinge member, consisting of a body portion 3 having an opening 4 extending

vertically therethrough and forming an eye, as shown. Secured to the back of the body portion 3 are horizontal strips 5, one at the top and one at the bottom. Secured to these strips 5 is a plate portion 6 forming a part 60 of a clamping plate 7 arranged at right angles thereto and having holes 8 therein for receiving screws or bolts. The plate and strips 5 form a transverse pocket 9 for the reception of a tongue 10 forming a part of 66 a clamping plate 11 which is provided with openings 12 for bolts or screws.

It will be seen from the foregoing description that the plate 11 and its tongue 10 may be moved outwardly to extend the 70 clamp of the hinge member to fit any suitable partition or frame. This type of clamping means for the hinge is utilized on the lower partition hinge member and may be used on door hinge engaging members 75 as shown in Fig. 6.

Engaging in the opening 4 is a pivot member 12 forming a part of a door engaging clamp member 13. This clamping member 13 is secured to the upper edge of 80 the door by bolts or screws 14.

The lower hinge structure comprises a main body portion 15 provided with a clamping means identical with that used in connection with the upper hinge structure. 85 The body portion is provided with an outwardly extending eye having an opening 16. Extending upwardly from this eye and forced into the opening 16 is a tubular pivot 17 upon which is mounted a cam sleeve 18 having a double cam 19 formed integral therewith. This sleeve 18 is held in any suitable position upon the tubular extension 17 by an adjusting screw 20.

The lower door hinge member comprises 95 a pivot portion 21 preferably formed integral with a door clamp 22 substantially identical with the upper door clamp 13 except that it is provided with a pair of downwardly extending ears 23 which receive a pin 24 100 upon which a roller 25 is rotatably mounted. This roller 25 engages the cam 19 as is clearly shown.

It is obvious that when the door is mounted on these hinges and it is swung to one side 105 or the other, it will return to normally closed position by its own weight. The upper and lower hinges are so placed upon the frame or partition that when the door is swung to one side and moves upwardly 110

through the action of the cam and roller, the upper door hinge member will finally engage the upper partition hinge member and limit the opening of the door. In other words, the location of the two hinges determines the extent of opening of the door and the upper hinge structure forms a stop.

In the modification shown in Figs. 7, 8 and 9, the upper hinge structure is the same as that employed in the other embodiment. The lower hinge structure, however, is arranged in a manner such that there is a closing tension on the door but the door does not raise as it is swung from one side to the other and this construction will now be described.

The frame engaging member is identical with that employed in the other construction, except that the tubular member 17 receives a cam sleeve 26 provided with a cam 27 similar to the cam 19 except that it has less pitch and that it is provided with a holding portion, which may be horizontal or may be very slightly inclined, as shown at 28, the inclination being insufficient to cause any tendency of the door toward movement into closed position. This surface 28 is provided with a depression at 29 which is just beyond the upper end of the cam 27. This depression is adapted to receive a roller 30 mounted in the lower end of a plunger 31 slidably mounted in a tubular guide 32 preferably formed integral with the lower door engaging hinge member 33. This tubular guide is spaced from the side clamping portions 34 and 35 of this lower hinge member so as to permit the door parts 36 to nest between the tubular guide and these clamping portions 34 and 35. The upper end of the tubular guide is closed and forms an abutment for a spring 37 which thrusts against the plunger and moves it downwardly so that its roller engages the cam surface with sufficient pressure to tend to close the door when the roller is on the cam 27. In order to prevent the rotation of the plunger, a recess 38 is provided in its side and this recess receives the end of a threaded pin 39 passing through the lower hinge member, as shown in Fig. 8. Pin 39 forms a stop to limit upward movement of plunger 31. When the parts reach holding position with the door open, as shown in Fig. 8, the pin 39 abuts against the lower end of the slot 38 and the cam effect is exerted to raise the door bodily and press the upper door hinge member 13 against the upper stationary hinge member and thereby limit opening movement of the door.

The upper hinge structure is substantially identical with that shown in the other figures of the drawing and this hinge structure and the lower one are so arranged that the door has no appreciable vertical movement between them. As in the other structure

the upper hinge member forms a stop by reason of the fact that the tendency of the roller 30 to ride up the slight incline 28 tends to produce a slight raising of the door which causes it to abut against the upper hinge partition member, thereby preventing any further opening of the door.

It will be seen from the foregoing construction that when the door is being opened the plunger will be moved upwardly against the tension of the spring 31 through the action of the cam 27. If the door is swung short of its full open position it will return automatically to closed position as in the gravity construction already described. The lower cam is made adjustable and reversible in both cases to position the door and to determine its normal closed position. These features, however, form a part of the copending application referred to and are only referred to herein as they may enter the combination of the specific features set forth.

What I claim is:

1. A door hinge, comprising a partition-
engaging member, a door-engaging member,
a cam carried by one of said members, a
spring-actuated plunger carried by the other
of said members and engaging said cam and
normally tending to move said door to a
predetermined position, said plunger being
provided with an elongated slot and pin
means engaging in said plunger slot for
limiting movement of said plunger to there-
by limit swinging movement of the door
away from said predetermined position.

2. A hinge member, comprising a body
portion having an eye for the hinge pivot,
plate members secured along upper and
lower marginal portions of the rear face of
said body portion, said plate members being
so arranged as not to extend beyond said
body portion, an angular plate member having
one face secured to said first named plate
members, thereby forming a slideway be-
tween the faces of said body portion and said
angular plate member, and a second angular
plate member having a portion slidable in
said slideway for adjusting said angular
plate members relative to each other to en-
able them to be secured to supports of vary-
ing thickness.

3. A hinged door and jamb structure, com-
prising an upper hinge member adapted to
be secured to a jamb, an upper hinge mem-
ber adapted to be secured to the door, a lower
hinge member secured to the jamb and be-
ing provided with a cam for elevating the
door upon being opened, a lower door hinge
member, and a spring actuated plunger car-
ried by said last named member, said plunger
engaging said cam and normally tending to
move said door into a predetermined posi-
tion, and means for limiting upward move-
ment of said plunger in said lower door hinge

member upon the door being opened to a pre-determined degree, said upper and lower hinge members being so spaced that the cam will cause the door to rise when the upward movement of said plunger is limited and thereby cause the upper door hinge member to engage the other upper hinge member and limit the opening movement of the door.

4. A hinged door and jamb structure, comprising an upper hinge member adapted to be secured to the jamb, an upper hinge member adapted to be secured to the door, a lower hinge member adapted to be secured to the jamb and having a cam for elevating the door when being opened, a lower hinge member adapted to be secured to the door and being provided with means for engagement with said cam member, said hinges being so spaced that said cam will cause the upper door hinge member to engage the other upper hinge member and thereby limit the opening movement of the door.
5. A door hinge, comprising a stationary member, a movable hinge member, one of

said members having an eye, a bearing sleeve 25 secured in said eye and extending beyond the same, the other member having a pin entering said sleeve, said pin and sleeve being arranged for relative rotation, and a cam member surrounding said sleeve for co-operation with said hinge member.

6. A door hinge, comprising a stationary member having an eye, a bearing sleeve secured in said eye and extending beyond the same, a movable hinge member having a pin 35 entering and rotatable in said sleeve, and a cam member surrounding said sleeve for co-operation with said hinge member.

7. A door hinge, comprising a stationary member having an eye, a bearing sleeve 40 secured in said eye and extending beyond the same, a movable hinge member having a pin entering and rotatable in said sleeve, and a cam member surrounding said sleeve and rotatably adjustable thereon and adapted for 45 cooperation with said hinge member.

In testimony whereof I affix my signature.
ARVID J. MALMBERG.
